UNITED STATES PATENT OFFICE.

GUSTAVE J. SENGBUSCH, OF MILWAUKEE, WISCONSIN, ASSIGNOR TO NEW ERA MFG. CO., OF NEW YORK, N. Y., A CORPORATION OF NEW YORK.

PENCIL-SHARPENER.

1,186,951.

Specification of Letters Patent. Patented June 13, 1916.

Application filed July 8, 1912. Serial No. 708,101.

To all whom it may concern:

Be it known that I, GUSTAVE J. SENGBUSCH, a resident of Milwaukee, in the county of Milwaukee and State of Wisconsin, have invented certain new and useful improvements in Pencil-Sharpener, of which the following is a specification.

My invention relates to pencil sharpeners and contemplates novel features of construction and operation.

My invention applies to that class of sharpeners in which a cutting blade is reciprocated substantially longitudinally of the pencil in the sharpener, and among the important objects of the invention are to provide a construction in which the knife will be automatically lifted to clear the pencil at each back stroke to thus avoid the tendency of the knife to draw the pencil out of the chuck during the back strokes; to provide a grinding wheel for the knife built in as a part of the sharpener so that the knife can be ground; to provide such arrangement that the knife will be brought up to and under the action of the grinding wheel at the end of each cutting stroke; to provide such arrangement for the grinding wheel and knife that the knife will be acted upon by the wheel for a certain time after each cutting stroke thereof; to provide improved mechanism for effecting reciprocation of the knife blade supporting frame so that said frame is positively and accurately moved in either direction; to provide improved ratchet mechanism for effecting step by step rotation of the pencil; and in general to provide improved and more efficient construction and operation in a device of the class referred to.

The device illustrated on the accompanying drawings embodies the various features of my invention and in these drawings Figure 1 is a side elevational view of a sharpener, Fig. 2 is a plan view thereof, Fig. 3 is a sectional view taken from plane 3-3' of Fig. 2; Fig. 4 is a front end view of the knife blade and its supporting frame, Fig. 5 is a plan view of the knife supporting frame, and Fig. 6 shows the mounting of the grinding wheel on its supporting axle.

The supporting structure for the sharpener comprises a cup-shaped frame 10 from whose sides extend the standards 11 and 12, and which has at its rear end the diagonal extension 14 provided with a bore 15 for

receiving a pencil to be sharpened, the top of the extension forming the inclined guide surface 16 for the cutting blade 17. A collar 18 supported across the mouth of the bore 15 journals a chuck 19 carrying spring 60 clips 20, for clamping the pencil inserted through the chuck, the outer flange of the chuck having ratchet teeth 21 for co-operating with the ratchet pawls to be described later. The bore 15 terminates at its inner 65 end at the opening 22 in the surface 16 through which opening the end of the pencil projects during the sharpening operation. The lower end of the surface 16 leads to the interior of the cup frame 10 to 70 guide the shavings thereto and a passage-way 23 leads from opening 22 to carry the graphite cuttings to the cup.

The extension 14 has side plates 24 and 25 secured thereto which extend beyond the surface 16 and at their upper edges are provided with inwardly extending flanges or guide tongues 26 and 27 parallel with the surface 16 and for receiving the grooves 28 and 29 of the block 30. This block has 80 downwardly extending lugs 31 and 32 at its sides which support a shaft 33 on which is hinged the knife supporting frame 34. The construction of this knife supporting frame is best shown in Figs. 4 and 5, the frame 85 having the dove-tailed channel 35 in its lower face for receiving the blade 17. A slot 36 extending a distance rearwardly from the front end of the frame, divides the front end of this frame, and a clamping 90 screw 37 passing through the part 34' and threading into the part 34" serves to draw these parts together to securely clamp the blade in adjusted position. A compression spring 38 interposed between the block 30 95 and frame 34 tends to hold the point of the blade against the surface 16 during reciprocation of the block. The frame 34 is somewhat narrower than the block 30 so that the outer end of lug 32 may form a cam abutment for the ratchet lever 39 pivoted at an intermediate point to the plate 25, the front end of this lever having the downwardly extending arm 40 for co-operating with the ratchet teeth 21 on the chuck 19. A spring 100 41 tends to pull the front end of the ratchet arm downwardly and when the block 30 is moved rearwardly, the front end of the ratchet lever is released from the lug 32 and the front end of the lever is swung 105 110

downwardly by the spring 41 and the chuck with the pencil therein is given a rotational advancement. Upon the forward stroke of the block 30 the lug 32 engages with the front end of the ratchet lever to raise the outer end 40 thereof for engagement with another ratchet tooth. A detent pawl 42 supported from the plate 26 locks the chuck in position after advancement by the ratchet lever. During each forward stroke of the knife blade the part of the pencil projecting above the surface 16 is shaved off and the friction of the blade on the pencil will keep the pencil end at the inner end of the bore 15 until the pencil has been sharpened all the way around to correspond with the conical surface 15' of the bore.

In order to prevent the knife from drawing out or displacing the pencil during back strokes, provision is made to raise the knife point to clear the pencil during such back strokes. The shank 37 of screw 37 extends laterally through the longitudinal opening 43 in the side plate 24, and coöperates with the cam plate 44. This cam plate has at its ends slots 45 and 46 extending partly vertically, and partly longitudinally of the plate, screws 48 and 49 threaded into the side plate 24 receiving these slots. A spring 50 secured to the cam plate and to the side plate 24 tends to hold the cam plate in its outer position with the lower ends of its slots in engagement with the screws 48 and 49, as shown in full lines in Fig. 1. This is the position whenever the knife blade is at the end of its forward stroke, the upper surface 44' of the cam plate extending into the opening 43 and into the path of the outward movement of the screw shank 37', the front end 44'' of this surface 44' being included downwardly so that the knife blade may assume its lowermost position. The outer end of the cam plate is cut away for a short distance to leave a shoulder 51 at the outer end of the surface 44'. As the block 30 and with it the knife frame 34 is moved rearwardly the shank of screw 37 will engage the incline 44'' and will reach the surface 44', the knife supporting frame 44 being thus swung upwardly to raise the knife edge above the surface 16 and above the pencil part projecting through opening 22, and this raised position of the knife frame is maintained until the screw 37 falls into the cut away part of the cam plate and behind the shoulder 51, the knife edge then being in engagement with surface 16 ready for the next cutting stroke. As the knife supporting structure is now moved forwardly the screw 37 will abut against the shoulder 51 and will carry the cam plate 44 forwardly a distance until the bends of the slots 45 and 46 reach the screws 48 and 49

whereupon the screws 48 and 49 will receive the vertical ends of the slots and the cam plate will drop so that its upper surface 44' will be removed from the path of the screw shank 37' so that the blade edge 70 may continue in engagement with the surface 16 to take a cut on the pencil. When the vertical sections of the slots in the cam plate reach the screws 48 and 49, the cam plate will be pressed downwardly by the force of the spring 38 acting against the knife frame 34 and such pressure will overcome the tendency of spring 50 to raise the cam plate. As soon as the knife supporting structure reaches the end of its forward stroke and the screw shank 37' has left the top of the cam plate, spring 50 will raise the cam plate and will shift it back to its normal position so that it will again form a rigid cam runway for the screw shank 37' during the next back stroke of the knife supporting structure. Thus during reciprocation of the knife supporting structure, the knife edge is automatically raised to clear the pencil during the back strokes and is automatically brought into cutting position during the forward strokes.

Coming now to the mechanism for reciprocating the knife supporting structure, the standards 11 and 12 support at intermediate points the shaft 52 which between the standards is deflected to form the crank loop 53, the outer end of the shaft carrying the actuating lever 54 provided with the handle 55. Supported between the upper ends of the standards 11 and 12 is a shaft 56 which pivots the swinging actuator plate 57. This actuator plate has the arcuate arms 58 and 59 between whose ends enters the lug 60 extending upwardly from the reciprocating block 30 of the knife supporting structure, this lug being engaged by the arm 58 to cause back strokes of the knife supporting structure, and is engaged by the arm 59 to cause the forward strokes as the cam plate 57 is swung forward and back. Extending through the arm 58 is a slot 61 whose inner and outer surfaces 62 and 63 form cam surfaces for the yoke 53' of the crank loop 53, which yoke extends through the slot 61. The slot 61 extends along the arc of a circle and when the plate 57 is in one position the slot 61 and the cam surfaces 62 and 63 will be concentric with the crank shaft so that the crank shaft may be rotated through the extent of the slot without causing movement of the actuator plate or of the knife mechanism. As shown, the slot 61 is of substantially 180 degrees extent so that for each half revolution of the crank shaft the knife structure will be at rest and during the remaining revolution of the crank shaft the knife supporting structure will be reciprocated. Describing

the operation more in detail, the crank is rotated in counter-clock wise direction (Fig. 3). As soon as the crank yoke 53 reaches the upper end of slot 61 it will, upon further movement, engage with the cam surface 62 to swing the actuator plate toward the left so that the knife supporting structure is moved outwardly to the position indicated in dotted lines. After the actuator plate has been swung to its outermost position toward the left, the crank yoke will engage with the cam surface 63 and the actuator plate will be swung toward the right and the knife supporting structure will be swung inwardly by the arm 59. At the end of such inward movement the slot 61 is concentric with the crank shaft and although the crank shaft continues to revolve there will be no further movement of the knife supporting structure until the crank yoke again reaches the outer end of slot 61, and the arcuate length of the slot determines the length of this period of rest of the knife supporting structure.

Sharpening means are provided for acting on the knife blade during each of the intervals of rest of the knife supporting structure and as shown, such sharpening means comprises a grinding wheel 64 mounted on a shaft 65 journaled in the sides of a yoke frame 66 whose ends are pivoted on the crank shaft so that the yoke frame together with the wheel may swing. The shaft 65 extends laterally through the elongated opening 67 in the standard 12 and at its outer end carries the pinion 68 which meshes with the gear 69 mounted on the crank shaft. Thus during rotation of the shaft the grinding wheel will be rotated and at the same time the wheel is free to swing bodily through a distance limited by the length of the opening 67. The wheel is positioned to engage with the knife blade end when the knife supporting structure is at the end of its forward stroke so that during the time that the crank yoke is coöperating with the slot 61 the wheel will be grinding and sharpening the blade. When the knife is withdrawn the wheel will move downwardly and when the knife is moved forwardly it first raises the grinding wheel so that during the grinding interval the weight of the wheel and yoke will supply the necessary pressure to effect efficient grinding. Thus after each cutting stroke of the knife, the knife will be ground and thoroughly sharpened and during the sharpening period the knife supporting structure is rigidly held in place by the actuator cam which is locked against movement by the crank loop engaging in the slot 61 while said slot is concentric with the crank shaft.

I thus provide a very efficient pencil

sharpener in which the knife is sharpened during operation of the cutter and before or after each cutting operation, and in which the knife is prevented from engaging with the pencil during the return strokes so that the pencil will not become displaced. The knife supporting structure is positively moved both forward and back and is rigidly held during the time that the knife is acted upon by the sharpening mechanism.

I do not, of course, desire to be limited to the exact construction and arrangement shown and described as modifications can be made which would still come within the scope of the invention and I claim the following:

1. In a pencil sharpening device, the combination of a support for a pencil, a cutting blade, a supporting structure for said blade reciprocable to effect cutting engagement of said blade with said pencil, a crank shaft, means intervening between said crank shaft and knife blade supporting structure for causing reciprocation of said supporting structure during only part of each revolution of the crank shaft, said supporting structure being at rest during the remainder of each revolution of the crank shaft, and sharpening means controlled by the rotation of said crank shaft to coöperate with the blade during such period of rest of the blade supporting structure.

2. In a pencil sharpening device, the combination of a support for pencils to be sharpened, a knife supporting structure reciprocable on said support, a blade carried by said knife supporting structure, a rotating element, cam mechanism connecting between said rotating element and said knife supporting structure to effect reciprocation of said structure during only part of each revolution of said rotating member, said supporting structure being at rest during the remainder of each revolution, and a sharpening member driven by said rotating member to sharpen the blade during such intervals of rest of the blade supporting structure.

3. In a pencil sharpening device, the combination of a support for pencils to be sharpened, a supporting structure reciprocable on said support and carrying a knife blade, a crank pin, means for revolving said crank pin, a cam member interposed between said crank pin and supporting structure and having cam surfaces to be engaged by said crank pin to effect reciprocation of said structure during only part of each revolution of said crank pin, and grinding mechanism coöperating with said blade during the remainder of each revolution of said pin.

4. In a pencil sharpening device, the combination of a support for pencils to be sharpened, a frame reciprocable on said support and carrying a knife blade, a crank pin

- and means for revolving the same, a cam member pivoted eccentrically with reference to the crank pin and having a cam slot for receiving said pin, said cam slot being concentric with the axis of revolution of said pin when said cam member is in one position whereby said cam member will remain stationary during engagement of said crank pin in said slot at such time, abutments on said cam member coöperating with said frame to effect reciprocation thereof as said cam member is swung after said crank pin reaches the end of said cam slot, and means for grinding said blade during said period when the cam member is stationary.
5. In a pencil sharpening device, the combination of a support for pencils to be sharpened, a frame reciprocable on said support and carrying a knife blade, a crank pin and means for revolving same, a swinging cam member having abutments for coöperating with said frame to effect reciprocation thereof during swing of the cam member, means connecting said cam member with said crank pin to effect swing of said cam member during only part of each revolution of said crank pin, and to hold it stationary during the remainder of the revolution, and means for grinding said blade when the cam member is at rest.
- 20 6. In a pencil sharpening device, the combination of a support for pencils to be sharpened, a frame reciprocable on said support and carrying a knife blade, a crank pin and means for revolving same, a swinging cam member having abutments for coöperating with said frame to effect reciprocation thereof during swing of the cam member, means connecting said cam member with said crank pin to effect swing of said cam member during only part of each revolution of said crank pin, and a continuously 25 rotating grinding wheel engaged by the blade during the remainder of each revolution.
- 40 7. A pencil sharpener having a frame with a cup portion near its bottom, a member extending upwardly from said cup portion and carrying a pencil holder, and supports extending into overhanging relation to the pencil holder; a cutter mounted to reciprocate in coöperative relation to the pencil

holder; actuating means mounted on the overhanging supports; and connections between the actuating means and the cutter and pencil holder for actuating the same; and a cutter sharpener freely suspended on the overhanging supports and swinging into coöperative relation with the cutter, whereby the latter may be sharpened at the end of its cutting stroke.

8. In a pencil sharpening device, the combination of a support for pencils to be sharpened, a supporting structure reciprocable on said support and carrying a knife blade, a crank shaft, cam mechanism connecting between said crank shaft and supporting structure for causing reciprocation of said structure, a frame hung from said crank shaft, a grinding wheel journaled in said frame, and means for causing engagement of said blade and wheel after each cutting operation of said blade.

9. In a pencil sharpening device, the combination of a support for pencils to be sharpened, a supporting structure reciprocable on said support and carrying a knife blade, a crank shaft, cam mechanism connecting with said crank shaft and supporting structure and adapted upon rotation of said crank shaft to cause reciprocation of said structure to sharpen the pencil, a grinding wheel having driven connection with said crank shaft and disposed to be engaged by the knife blade at the end of each cutting stroke and prior to the return stroke.

45 10. In a pencil sharpening device, the combination of a support for pencils to be sharpened, a reciprocating support carrying a knife, means for reciprocating said support to carry the knife back and forth over a pencil to be sharpened, a grinding wheel operating in the path of movement of the knife and near the end of said path, and means for actuating said wheel, whereby the knife, as it nears the end of its cutting movement, engages said wheel and is sharpened thereby.

In witness whereof, I hereunto subscribe my name, this 3rd day of July, A. D. 1912.

GUSTAVE J. SENGBUSCH.
